UNITED STATES PATENT OFFICE.

FRANK W. VAN NESS, OF MILWAUKEE, WISCONSIN, ASSIGNOR, BY MESNE ASSIGNMENTS, TO RICHMOND RADIATOR COMPANY, OF NEW YORK, N. Y., A CORPORATION OF DELAWARE.

ELECTRICAL CONTROLLER.

1,153,978.

Specification of Letters Patent. Patented Sept. 21, 1915.

Application filed April 18, 1910. Serial No. 556,093.

To all whom it may concern:

Be it known that I, FRANK W. VAN NESS, a citizen of the United States, residing at Milwaukee, in the county of Milwaukee and 5 State of Wisconsin, have invented certain new and useful Improvements in Electrical Controllers, of which the following is a specification, reference being had to the accompanying drawing, forming a part 10 thereof.

This invention relates to an electrical controller for vacuum cleaning systems and the like, and the objects of the invention are to provide an electrical controller which is 15 simple in construction so as not to get out of order easily, which can be depended upon to positively open or close an electric circuit without fail, which will positively keep the circuit closed, and which will readily respond to changes in the pressure existing in 20 the vacuum system in such a manner that the pressure actuated part of the controller will move to its predetermined limits of stroke upon the establishment of the predetermined pressures in the vacuum system, 25 so that the electric switch will be immediately and positively opened or closed.

Preferably the electric switch of the controller is constructed to act on the principle 30 of a snap switch to prevent arcing when the switch is opened or closed, but the structure of the controller is such that the switch is positively opened or closed by the pressure-actuated member, should the switch 35 stick to the contact through which it completes the circuit, or should the elements of the controller which cause the switch to act on the principle of a snap switch fail to perform their intended function properly, in 40 the manner to be hereinafter specifically described.

Referring to the drawings which accompany this specification and form a part thereof, which drawings illustrate an embodiment of this invention and on which drawings the same reference characters are used to designate the same parts wherever they may appear in each of the several views, Figure 1 is a side elevation of the 45 controller, the top casing being shown in section; Fig. 2 is a vertical section taken on the line $a-a$; Fig. 1, looking in the direction indicated by the arrows; and Fig. 3 is a plan view of the top of the controller, the 50 top casing being omitted.

Referring specifically to the drawings, the reference numeral 1 designates a cylinder provided with a flanged head 2, which is preferably formed integral with the body of the cylinder 1. The opposite end of the cylinder is preferably enlarged transversely and symmetrically on opposite sides of the cylinder, as shown and designated by the reference numerals 3 and 4, whereby a hollow V-shaped extension is provided extending 60 from the end of the cylinder 1. The cylinder is provided with a bracket 5, by which the controller can be readily bolted to any suitable and convenient support. The lower open end of the cylinder and the 65 hollow V-shaped extension thereon is adapted to be closed by a cover plate 6, which is secured to the cylinder casting by bolts 7 or other suitable fastening means, so that an air tight joint is formed between the cover 70 and the cylinder casting. A pipe 8 affords communication between some part of the vacuum cleaning system in which a vacuum is maintained and the interior of cylinder 1 and cap 6 below the piston 9 in cylinder 1. 75

The cylinder 9 as illustrated, is shown as a hollow trunk piston provided with packing grooves 10 on the exterior thereof to prevent the passage of air by said piston between it and the cylinder. The head 11 of the piston is provided with a boss or projection 12, which is adapted to seat against a leather washer 13, retained in a cavity 14 in the head 2 of the cylinder. The piston has secured thereto a piston rod 15 which projects through the aperture 16 in the cylinder head 2 and on its end carries a yoke member 17. The yoke member 17 is composed of two parts, viz.: a lug 18 of suitable insulating material, secured to the piston rod 15 by a pin 19 or other suitable means, and a yoke member proper 20, secured to said lug by a pin 21 or other suitable means. The head 2 of the cylinder has a recess 22 in its outer face within which is seated a leather washer 23, against which the lug 18 is adapted to seat. The function of the leather washers 13 and 23 is to absorb the shock caused by the movements of the piston 9, yoke member 17 and piston rod 15. 90

The piston 9 is preferably provided with a spider 24 in the interior thereof provided with two diametrically disposed lugs 25 and 26, and the cover 6 is provided with oppositely disposed lugs only one of which is 100 105 110

shown by the drawings and designated by the reference numeral 27. The lugs 27 support a pivot pin 28 upon which is supported an equalizing lever 29 provided with two oppositely extending arms 30 and 31. The ends of arms 30 and 31 are provided with spring seats 32 and 33 pivotally secured thereto, and spring seats 34 and 35 are pivotally secured to lugs 25 and 26. Springs 36 and 37 of the open or compression type are seated on the spring seats 32 and 34 and 33 and 35 respectively, said springs being disposed at an angle with respect to the axis of cylinder 1 and the direction of movement 10 of piston 9 in the manner as shown by Fig. 2 of the drawings.

The numeral 38 designates a drain plug in the bottom of the cover 6 to drain off any water of condensation which may collect in said cover.

The numerals 39 and 40 designate apertures in the head of the cylinder 1 by means of which free communication is established between the atmosphere and the space within 25 the cylinder above the piston 9.

The numeral 41 designates a standard secured to the flange top 2 of cylinder 1 and suitably insulated therefrom by insulating material 42. The numeral 43 designates another standard secured to the flanged top 30 of cylinder 1 and suitably insulated therefrom by insulating material 44. The standard 41 is provided with a laterally projecting arm 45 from which depends a carbon contact block 46 which is in electrical communication with a conducting wire 47.

Pivoted on standard 43 is a bell crank lever 48, which is loosely connected by one of its arms to a pin 49 on yoke 20. To its 40 other end is secured a spiral spring 50, which is also secured to a rocker 51, above the pivot 52 therefor. A bent switch member 53, is secured to the rocker 51, and passes through the yoke 20. A conducting wire 54 45 is secured to rocker 51, and is provided with a helical portion 55, which permits of movement of the rocker 51 on its pivots 52. The switch 53 passes between a pin 56 secured to yoke 20, and the top of yoke 20 has a 50 downwardly extending projection 57, adapted to contact with switch 53 to pull switch 53 away from the carbon contact 46 under certain circumstances to be hereinafter stated.

55 It will be noted that as the piston 9 moves downwardly within cylinder 1, the bell crank lever 48 will be rocked on its pivot, thereby bringing the end of the spring attached to said bell crank lever 48 on the 60 other side of pivot 52 from that shown by Fig. 2 of the drawing, and it will be readily recognized that when the end of spring 50 is carried by the pivot 52 by the movement of the bell crank lever 48, the spring 50 will 65 swing the rocker 51 and switch 53 down-

wardly quickly, thereby snapping switch 53 away from the carbon contact 46, and this action will occur before the projection 57 on yoke 20 touches switch 53. It is also evident that when the switch is open and the piston 9 moves upwardly within the cylinder 1, the bell crank lever 48 will carry the lower end of spring 50 to the right hand side of the pivot 53, as shown by Fig. 2 of the drawings, and the spring will tilt the 75 rocker 51 into the position shown by Fig. 2 of the drawings, quickly, thereby snapping switch 53 against the carbon contact 46, in the same general manner that snap switches are commonly actuated.

80 It will be noted by reference to Fig. 2 of the drawings, that when piston 9 is in its elevated position, as shown, pin 56 bears against the lower side of switch 53 and presses said switch 53 firmly against the 85 carbon contact 46, thereby maintaining a good and firm contact.

The function and effect of the springs 36 and 37 in the inclined positions shown, is to exert a certain pressure against piston 9, 90 to maintain it in its elevated position, as shown, until a predetermined difference in pressure is established in the vacuum system between the vacuum existing therein and atmospheric pressure. The selected 95 predetermined pressure can be readily established by using springs of the required strength, and with the arrangement as shown and described, the piston 9 will move up or down under the influence of changes 100 of pressure in the vacuum system in a manner which will be readily understood.

The switch 53 being bent as shown, makes a rubbing contact with the carbon contact 46, so that said switch is kept clean and 105 pitting of the switch and the carbon contact at the points where the main current passes, are obviated. This rubbing contact is accentuated by the pin 56 pressing switch 53 against the contact 46.

110 The piston 9 is the pressure actuating part of the apparatus, and is responsive in its movements to differences of pressure existing within the vacuum system and the atmosphere.

115 The numeral 58 designates a cap or casing for the electrical part of the controller to inclose said part and protect the electrical parts from dust and dirt.

120 The rocker 51 and switch 53 are made as light as is advisable with the particular current to be carried, so that spring 50 will only have a small amount of work to do, and can snap or move said parts very quickly. It might happen that switch 53 would become 125 fused or stuck to contact 46, so that spring 50 would not be strong enough to snap the switch 53 away from contact 46, on the downward movement of piston 9. Under such a condition the circuit would remain 130

closed, but the projection 57 provides means for pulling switch 53 away from contact 46.

The switch 53 is intended to open or close the electric circuit within which is included an electric motor for operating the exhausting pump or other device which creates and maintains a vacuum in the system, and it will be readily apparent that when the proper degree of vacuum desired has been reached, which is determined by the strength of springs 36 and 37, piston 9 will be forced to its extreme lower position, thereby separating switch 53 from contact 46 and cutting off the supply of current to the motor or other apparatus which creates a vacuum in the system. On the other hand, when the circuit is open and the pressure in the vacuum system rises, piston 9 will be forced to its extreme upper position, thereby contacting switch 53 with contact 46 and holding said switch against said contact by the pin 56.

I am aware that many changes in structural details may be made from those disclosed by the drawings and described in this specification, but

What I claim is:

In an electrical controller, the combination of a bell crank lever provided with a

pivot, a rocker pivoted adjacent the pivot 30 of the bell crank lever and in the same general direction from the pivot of the bell crank lever in which one of the arms of the bell crank lever extends, a spring connected to the end of that arm of the bell crank lever 35 and extending substantially in line therewith and connected with the rocker at a point remote from its pivot, a flexible switch member carried by the rocker, a contact for said switch member, a reciprocatable yoke 40 member embracing said flexible switch member and provided with means to contact with said flexible switch member when the yoke is reciprocated in either direction, one of said means being adapted to hold said flexible switch member against said contact, and the other of said means being adapted to force said flexible switch member away from said contact when stuck thereto, said yoke member being pivotally connected with said 50 bell crank lever, and means adapted to reciprocate said yoke member.

In witness whereof I hereto affix my signature in presence of two witnesses.
